SPINNING FRAME

Walter S. Eastman and Richard Patterson, Glendale, R. I., assignors to Stillwater Worsted Mills, a corporation of Rhode Island

Application June 4, 1940, Serial No. 338,791

17 Claims. (Cl. 19—130)

This invention relates to spinning frames.

It has among its objects to provide an improved frame of the type wherein the twisting process is divorced from the drafting process performed by the front rolls and twisting occurs after the yarn passes off of supplemental pressure means acting on the top front roll of the drafting mechanism. A further object is to provide an improved pressure mechanism comprising individual pressure means of an improved construction and disposed and individually movable in an improved manner on said frame and each cooperating with the top roll of a different set of front rolls. Another object is to provide such an improved mechanism utilizing pressure rolls and wherein each pressure roll has an exposed free end in such manner as markedly to facilitate removal of a "lap" from the same while eliminating the necessity for interfering with the operation of other rolls or for shutting down the spinning frame. A still further object of this invention is to provide an improved construction whereby such improved individual mechanisms are mounted in an improved manner on the spinning frame and disposed in an improved relation to the fluted and top front rolls of the drafting mechanism. Still another object of this invention is to provide such an improved mechanism whereby the spinning frame is adapted to operate at substantially higher speeds while enabling a substantial reduction in necessary interruptions and further reducing yarn breakage. Another object of our invention is to provide an improved pressure mechanism attachment including such an improved pressure roll and associated pressure mechanism and adapted to be applied to a standard spinning frame with a minimum of change therein while enabling the above improved results to be obtained. These and other objects and advantages of this invention will, however, hereinafter more fully appear.

In the accompanying drawing, one form which this invention may assume in practice is shown for purposes of illustration.

In the drawing:

Figure 1 is a sectional end elevation of a spinning frame equipped with this improvement;

Fig. 2 is a partial front elevation of the same;

Fig. 3 is a sectional view on line 3—3 of Figure 1, and

Fig. 4 is a perspective view of the roller carrying end of the improved attachment, the roller being shown separated from its carrying member to facilitate illustration.

In this illustrative construction, a spinning frame of standard construction is shown, including drafting mechanism having on its carriage stand 1, suitable drafting mechanism including usual fluted lower front rolls 2 and cooperating cork covered top front rolls 3, as well as usual closed pigtail guides 4 and usual whirled bobbins 5 disposed under usual caps 6; improved pressure mechanism herein being provided and cooperating with the top front roll 3 to effect twisting and divorce the same from the drafting function of the rolls 2 and 3.

Referring more particularly to the pressure mechanism, it will be noted that an individual pressure mechanism is provided for each set of rolls 2, 3. Of these individual mechanisms, each herein, moreover, includes a single pressure roll 7 of hard wood or other material having a coefficient of friction adapting it to cooperate with the cork roll 3, and of substantially the width of the roll 3 and engaging the underside of the latter, so that the point at which the yarn passes off of this roll 7 is directly above the center of the guide 4. As shown, this roller 7 is carried on the front end of a rearwardly extending swinging frame, generally indicated at F, having a front portion 8 provided with a lateral extension 9, herein integral and extending through a suitable axial bore 10 in the roll 7. Also, this extension 9 herein carries on its inner end a suitable abutment or bearing in the form of a roller or disc 11 spacing the roller 7 from the body of the portion 8. Also, the roll 7 is suitably positioned on the free end of this arm by a washer and cotter connection 12. The portion 8 herein also extends rearwardly from the roll 7 alongside the fluted roll 2 and above and across the shaft thereof. Herein, this frame F is also provided with a short transverse portion 13 intermediate its ends and suitably fixed, as by welding, to the upper curved surface of an elongated semi-tubular bearing member 14 journaled on a suitable length of round rod 15 welded to, and extending longitudinally of, the upper edge of the front saddle bar 16. As shown, the frame F also has a rearwardly extending portion 17 disposed substantially in the vertical plane of the rolls 2 and 3 and carrying a suitable weight 18 on a hook 19 on the rear end of this portion 17.

In the operation of this improved construction, the twisting function is divorced from the drafting function of the rolls 2 and 3 and the hard wood pressure roll 7 is pressed against the underside of the cork top roll 3 and rotated

thereby while the yarn is pressed against the bottom of the roll 3, and twisting occurs as the yarn passes off of the rolls 7 in such manner as to produce a continuous twist extending from the latter roll down under the cap 6, while the twisted yarn continuously engages with the entire closed periphery of the pigtail 4, all as is usual in devices of this type. However, herein it will be observed that the several rolls 7 are all independent of one another, each being carried on its own frame F and independently movable relative to the other rolls 7 into and out of operative relation with its cork top roll 3. Further, the end of each pressure roll 7 is exposed in such manner that, should a "lap" occur, the operator may readily remove the same and reconnect the yarn from this open end of the roll, while the spinning frame continues in operation and without disturbing the operation of any other roll 7. Further, it will be observed that a separate 20 pivoted and weighted frame F acts to hold each roll 7 pressed against the yarn and its roll 3 while enabling the front end of the frame to be depressed readily whenever it is desired to obtain access to a "lap." Attention is also directed to the fact that herein the extensions 9 on adjacent frames F are directed toward each other and spaced apart in such manner as to permit free access between the same to the ends of the rolls 7 while also permitting an operator to have 25 access to either of these adjacent rolls 7 and thus reducing the number of stations necessary for the operator, while making all of the rolls 7 readily accessible.

As a result of this improved construction, it is made possible, while obtaining the materially stronger yarn resulting from the use of such pressure roll mechanism, also very materially to increase the possible production while utilizing such a mechanism, through reducing the delays heretofore incident to the use of the same. Thus, all necessity for shutting down the frame when a "lap" occurs is eliminated, at the same time that, through the improved individual pressure mechanisms for each pressure roll, it is also made possible materially to reduce the yarn breakage. The improved arrangement of adjacent rolls 7 with adjacent exposed ends also markedly facilitates the work of the operator, while the individual pressure rolls and individual pressure mechanisms therefor also make it unnecessary to disturb any other roll when any individual roll 7 requires attention as, for example, when a "lap" occurs thereon. As a result of these improvements, it is also made possible quite substantially to increase the speed of the frame as compared with prior constructions, while reducing the vibration of the rolls 7 which tends to break the yarn. Attention is also directed to the fact that the only change required in a standard frame is the provision of suitable pivots for the swinging frames F, while, if desired, these may be preformed on the frames and thus eliminate all necessity for change. These and other advantages of this improved construction will, however, be clearly apparent to those skilled in the art.

While in this application there is described one embodiment which the invention may assume in practice, it will be understood that the same is shown for purposes of illustration, and that the invention may be modified and embodied in various other forms without departing from its spirit or the scope of the appended claims.

What we claim as new and desire to secure by Letters Patent is:

1. In a spinning frame, drafting mechanism including cooperating front rolls, and an individually mounted pressure mechanism extending between the axes of said rolls and carrying an individually mounted pressure means for pressing the yarn against the top front roll.
2. In a spinning frame, drafting mechanism including cooperating front rolls, and pressure mechanism including yarn supporting means located in front of the nip of said front rolls, and means including a pivoted frame carrying said yarn supporting means and extending between the axes of said rolls for actuating said supporting means to press the yarn against the top front roll.
3. In a spinning frame, drafting mechanism including cooperating front rolls, and pressure mechanism for pressing the yarn against the top front roll including a pressure means located in front of the nip of said front rolls and a swinging mount having a lateral extension thereon on which said pressure means is carried.
4. In a spinning frame, drafting mechanism including cooperating front rolls, and pressure mechanism for pressing the yarn against the top front roll including a pressure means in front of the nip of said front rolls and a swinging frame pivoted in rear of said front rolls and carrying said pressure means on its front end.
5. In a spinning frame, drafting mechanism including cooperating front rolls, and pressure mechanism for pressing the yarn against the top front roll including a pressure means in front of the nip of said front rolls and a swinging frame pivoted in rear of said front rolls and carrying said pressure means on its front end and having balancing means in rear of its pivot.
6. In a spinning frame, drafting mechanism including cooperating front rolls, and pressure mechanism for pressing the yarn against the top front roll including a pressure means in front of the nip of said front rolls and a frame pivoted in rear of the lower roll of said front rolls and extending longitudinally alongside the latter and having a lateral extension on its front carrying said pressure means.
7. In a spinning frame, drafting mechanism including cooperating front rolls, and pressure mechanism for pressing the yarn against the top front roll including a pressure means in front of the nip of said front rolls and a frame pivoted in rear of the lower roll of said front rolls and extending longitudinally alongside the latter and having a lateral extension carrying said pressure means and a rearward extension normally biasing said roll to operative position and disposed substantially in the vertical plane of said lower roll.
8. In a spinning device, a frame having a front saddle bar, drafting mechanism on said frame including cooperating front rolls adjacent said bar, and pressure mechanism for pressing the 65 yarn against the underside of the top front roll including a pressure means and a supporting frame for said pressure means pivoted on said front saddle bar.
9. In a spinning device, a frame having a front saddle bar, drafting mechanism on said frame including cooperating front rolls adjacent said bar, and pressure mechanism for pressing the 75 yarn against the underside of the top front roll including a pressure means and a supporting frame for said pressure means pivoted on said

front saddle bar and including a frame member extending longitudinally alongside the lower front roll and having a lateral extension under the top front roll carrying said pressure means.

10. In a spinning device, a frame having a front saddle bar, drafting mechanism on said frame including cooperating front rolls adjacent said bar, and pressure mechanism for pressing the yarn against the underside of the top front roll including a pressure means and a supporting frame for said pressure means having a transversely extending bearing member overlying and pivoted on the upper edge of said saddle bar and frame portions extending in front and rear from said bearing member respectively carrying said pressure means and means biasing the latter into operative position.

11. In a spinning device, a frame, drafting mechanism on said frame including cooperating front rolls, and pressure mechanism for pressing the yarn against the underside of the top front roll including a pressure means and a supporting frame for said pressure means pivoted intermediate its ends on said frame and having said pressure means mounted on its front end and means disposed in rear of the frame pivot biasing said pressure means to operative position.

12. In a spinning frame, drafting mechanism including adjacent sets of cooperating front rolls, separate pressure means in front of the nip of said front rolls and pressing the yarn against the top front rolls, and individually movable pressure mechanisms for said pressure means individually pressing different strands of yarn and different pressure means against different top front rolls.

13. In a spinning frame, drafting mechanism including adjacent sets of cooperating front rolls, separate pressure means in front of the nip of said front rolls and pressing the yarn against the top front rolls, and individually movable pressure mechanisms for said pressure means cooperating with adjacent top rolls and individually pressing different strands of yarn and different pressure means against said different top front rolls including laterally spaced lateral supports for said pressure means extending toward each other and presenting exposed free ends of the latter.

14. In an attachment for spinning frames having front drafting rolls, pressure mechanism including a pressure means engageable with the yarn to press the same against the top front roll

5 in front of the nip of said front rolls, and generally horizontally disposed frame means for maintaining said pressure means in operative relation with said top front roll including a frame having a pivot intermediate its ends and having 10 said pressure means and counter-balancing means for the latter at opposite ends of said frame.

15. In an attachment for spinning frames having front drafting rolls, pressure mechanism including a pressure means engageable with the top front roll in front of the nip of said front rolls, and means for maintaining said pressure means in contact with said top front roll including a movable frame adapted to be mounted on said 20 spinning frame and having a lateral extension on its front end carrying said pressure means.

16. In an attachment for spinning frames having front drafting rolls, pressure mechanism including a pressure means engageable with the 25 yarn to press the same against the top front roll in front of the nip of said front rolls, a swinging frame adapted to be mounted on said spinning frame and having a lateral extension on its front end carrying said pressure means, a rearwardly located pivot, and means in rear of said pivot 30 for maintaining said pressure means in operative relation to said top front roll.

17. In an attachment for spinning frames having front drafting rolls, pressure mechanism including a pressure means engageable with the 35 yarn to press the same against the top front roll in front of the nip of said front rolls, and a swinging frame comprising a rod having a laterally extending portion intermediate its ends and 40 an oppositely extending lateral extension on one end carrying said pressure means, a bearing member on said portion, and means acting on the opposite end of said rod for biasing said pressure means into operative position against a top front 45 roll.
